UNITED STATES PATENT OFFICE.

MAX GOETZE, OF STURGIS, SOUTH DAKOTA, ASSIGNOR OF SEVEN-EIGHTHS
TO WILLIAM C. BUDERUS, OF SAME PLACE.

LAMP-EXTINGUISHER.

SPECIFICATION forming part of Letters Patent No. 627,667, dated June 27, 1899.

Application filed June 13, 1898. Serial No. 683,385. (No model.)

To all whom it may concern:

Be it known that I, MAX GOETZE, of Sturgis, in the county of Meade and State of South Dakota, have invented a new and useful 55
5 Lamp-Extinguisher, of which herein follows a full, clear, and exact description, and which invention is a companion piece to one of a lamp-extinguisher patented under Letters Patent No. 484,362, dated October 11, 1892.

10 This invention relates to an improved safety-extinguisher for bracket, hanging, and chandelier lamps, as well as hand and stand lamps, and has for its object to provide a novel simple attachment for a lamp having a round wick-tube which will automatically cover the top of such wick-tube and wick in the burner and extinguish the light when the chimney is removed, dropped, or knocked off, this round-burner lamp being now nearly exclusively 15 used for bracket, hanging, and chandelier lamps in hotels, warehouses, offices, &c., also railroad-cars, vessels of all kinds, &c., where accidents are most liable to happen and where the danger from accidents is so much enhanced by the setting of fire to them by falling or exploding lamps. My lamp-extinguisher will remove all such dangers from fire if generally and properly used, because the light of the lamp will be immediately extinguished 20 whenever the chimney comes off by force of the accident if the chimney is secured as hereinafter described.

To this end my invention consists in the peculiar construction of parts, as hereinafter described and claimed.

35 Reference is to be had to the accompanying drawings, forming a part of this specification, in which drawings similar letters of reference indicate corresponding parts in the figures.

40 Figure 1 in the drawings is a side view of the extinguisher itself separate from the lamp-burner. Fig. 2 is a side sectional view of the lamp-burner with extinguisher inserted with broken chimney and showing the extinguisher when down, while the lamp may be lighted and kept burning. Fig. 3 is a side sectional view of the lamp-burner with extinguisher inserted, the chimney being off and the extinguisher being up after extinguishing the light.

45 50 My extinguisher, Fig. 1, is inserted in the burner between its outside part and the round

wick-tube. It consists of a metal ring *a* just as much larger than the wick-tube as to easily slip up and down. This is attached to and rests upon a spiral spring *b* of the same circumference as the ring *a* and is large enough to rest upon the bottom plate of the burner when unpressed and bringing the ring *a* nearly on line with the plate of the burner upon which the chimney rests. To the outside of this ring *a* are attached, by small springs *c*, six gates *d*, of copper or brass, which gates *d* so attached to the ring *a* are a small distance apart and are somewhat concave and grow a little narrower toward the top, so as to close over the burning wick and inclose the air-distributer, around which the wick burns, and thereby extinguish the light.

55 My extinguisher is controlled by two springs *e*, which are attached to the ring *a* opposite each other, and which springs extend to the outside of the burner horizontally at *e'* through incisions cut into said outside part of the burner long and wide enough to allow said springs to freely move up and down. 75 Said springs are then bent upward at *e''* and go through holes in the plate of the burner upon which the chimney rests, as shown in Figs. 2 and 3 at *A A*, so as to give the chimney room to pass between them. They are bent inward 80 a little at *e'''*, so as to press upon the chimney, and are then bent outward again, forming arms *e''''*, by which the extinguisher may be pressed down.

85 In ordinary position, Fig. 3, when the chimney is off the gates close over the wick, and when the lamp is to be lighted, the arms *e''''* are pressed down, so that the spiral spring *b* is pressed against the bottom of the burner and the notches *f* on spring *e* will catch in the 90 plate of the burner upon which the chimney rests. The extinguisher is then open, and the lamp may be lighted and the chimney placed on, and the lamp is in working order or burning, Fig. 2. Whenever the chimney is taken 95 off or is knocked off, the springs *e* are set free, the spiral spring *b* will expand, taking the ring *a* and the gates *d* up with it, and the gates will close over the light and extinguish the same.

100 It must also be mentioned that as a necessary part of the invention, in case of bracket,

hanging, or chandelier lamps, it is needful that a copper wire be attached to the lower or upper part of the chimney by means of a loop in the wire, and which wire should be fastened to the wall. This contrivance is necessary to make sure that the chimney will come off the lamp in case the lamp falls or is knocked out of place in an accident, so as to make sure that the extinguisher will do its

10 work and prevent the light from setting fire to the apartment or the lamp from exploding.

If it is desired to remove the chimney without extinguishing the lamp, the arms e^4 may be held down with the fingers or otherwise, 15 so that the notches f in the springs e will stay in place in the plate at A A, and the chimney may then be so removed.

Having thus fully described my invention, I claim as new and desire to secure by Letters 20 Patent—

In combination with the outer part of a

lamp-burner and the wick-tube within the same, an extinguisher consisting of a ring adapted to slip up and down on the said wick-tube and the upwardly and inwardly curving 25 springs c and gates d supported by the said tube, a spring supporting the said extinguisher, chimney-holding springs e attached to the said ring, and provided with notches adapted to engage the burner when the chimney is in place, the dislodgment of the said chimney by the upsetting of the lamp leaving the said springs free to move inward, disengaging themselves from the said burner and allowing the extinguisher to slide downward on the inverted wick-tube, substantially 30 as and for the purpose set forth.

MAX GOETZE.
